(57) **CLAIM**

We claim the ornamental design for a screw-top container, as shown and described.

DESCRIPTION

FIG. 1 is a perspective view of an embodiment of the claimed design;

FIG. 2 is a front view of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1; and,

FIG. 6 is a top view of the claimed design of FIG. 1.

The broken lines seen immediately adjacent the shaded areas represent the bounds of the claimed design while all other broken lines are included for the purpose of illustrating portions of the screw-top container; the broken lines form no part of the claimed design.
